(57) **CLAIM**

The ornamental design for a vertical connection spring-cage
PCB terminal block, as shown and described.

DESCRIPTION

FIG. 1 is a top, front and left side perspective of the vertical
connection spring-cage PCB terminal block showing my new
design;

FIG. 2 is a front elevational view thereof;

FIG. 3 is a right side elevational view thereof;

FIG. 4 is a rear elevational view thereof;

FIG. 5 is a bottom plan view thereof;

FIG. 6 is a top plan view thereof; and,

FIG. 7 is a left side elevational view thereof.

The broken line portion in the drawing views is included to
show environment only and forms no part of the claimed
design.
